UNITED STATES PATENT OFFICE.

ADELINA J. VANSTROM, OF JAMESTOWN, NEW YORK.

MILK-BOTTLE CASE.

1,267,292.

Specification of Letters Patent. Patented May 21, 1918.

Application filed October 23, 1916. Serial No. 127,194.

To all whom it may concern:

Be it known that I, ADELINA J. VANSTROM, a citizen of the United States, residing at Jamestown, in the county of Chautauqua and State of New York, have invented certain new and useful Improvements in Milk-Bottle Cases, of which the following is a specification.

This invention relates to an improved bottle case in which a milk bottle may be placed and the principal object of the invention is to provide a case which will be of the vacuum type and which will be so constructed that a milk bottle may be placed in the case and milk kept cool, the case being so constructed that the bottle may be easily put in place and also easily removed when the upper portion of the case is removed from the lower portion.

Another object of the invention is to so construct this case, that the upper portion may be entirely removed from the lower portion, each having its own vacuum chambers, thus preventing the vacuum from being destroyed, when the upper portion or cover is removed.

Another object of the invention is to so construct this case that it may be formed of sheet metal and to further so construct it that it will be greatly strengthened thus preventing damage to the case when in use.

This invention is illustrated in the accompanying drawings wherein there is disclosed a view showing the case in vertical section with a bottle in place.

The body portion of this case is provided with an inner wall 10 and an outer wall 11, each of which is provided with a bottom disk indicated by the numerals 12 and 13 respectively. These disks are curved transversely as clearly shown in the drawing and contact thus provide a very strong bottom which will be braced and therefore cannot be easily bent or broken by a bottle dropping into the body portion of the case. The upper portion of the outer wall 11 is bent inwardly to provide an abutment seat 14 upon which a gasket may be placed if desired and is then carried upwardly and threaded to provide an externally threaded neck 15. This neck terminates in a flat face 16 forming a part of the inner wall 10.

The cap is provided with inner and outer

walls 17 and 18 and is provided with heads 19 and 20 curved transversely and contacting as clearly shown thus providing a strong head for the cap which will resist the force of a blow received in case anything should drop upon the cap. The cap is tapered and has the lower end portion of the inner wall 18 bent outwardly to provide a seat 21 against which the end of the neck of the body fits when the cap is screwed upon the neck. The wall is then threaded as shown at 22 so that the cap may be screwed upon the neck 15 and terminates in a flat face 23 for fitting upon the seat 14 or gasket carried thereby. The gasket has not been shown as this gasket may be used or not as desired and may be placed either upon the seat 14 or upon the seat 21. It will thus be seen that both the cap and the body portion are provided with vacuum chambers and that when the bottle is placed in the body portion and the cap screwed tight, the milk contained in the bottle will not lose its coolness.

What is claimed is:—

1. A case comprising a pair of detachable sections open at one end, the said sections being adapted to be assembled with their open ends abutting, each section comprising a pair of spaced inner and outer walls extending throughout the length of said sections and providing between them a vacuum chamber, the inner walls of said sections being bowed outwardly at their closed ends, and the corresponding portions of the outer wall of said sections being bent inwardly and into engagement with the said inner walls.

2. A case comprising a pair of detachable sections each being open at one end and being of equal diameter at their open ends, each of said sections comprising a pair of spaced walls connected at the open ends of the sections and providing vacuum chambers between them, each section at its open end having a relatively short annular upstanding wall, the said upstanding walls being spaced substantially equidistant from the inner and outer spaced walls of said sections and being formed integral with the said spaced walls at their opposite ends, the connecting portions for the upstanding walls and the said spaced inner and outer walls being disposed at right angles to the

latter and forming abutment surfaces, co-operating threads formed integral upon said vertical walls and being co-extensive therewith, and the abutment surfaces of said 5 sections being adapted to engage snugly with each other when the said sections are assembled.

In testimony whereof I affix my signature in presence of two witnesses.

ADELINA J. VANSTROM.
